UNITED STATES PATENT OFFICE.

WILLIAM T. JONES, OF DETROIT, MICHIGAN, ASSIGNOR TO THE EDMUNDS & JONES MFG. CO., OF DETROIT, MICHIGAN, A CORPORATION OF MICHIGAN.

LAMP.

1,058,181.

Specification of Letters Patent.

Patented Apr. 8, 1913.

Application filed September 11, 1911. Serial No. 648,751.

To all whom it may concern:

Be it known that I, WILLIAM T. JONES, a citizen of the United States, residing at Detroit, in the county of Wayne, State of Michigan, have invented certain new and useful Improvements in Lamps; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to pillar lamps especially designed for use upon limousines but adaptable for other purposes, and consists in the construction and arrangement of parts hereinafter more fully set forth and 20 pointed out particularly in the claims.

The primary object of the invention is to produce a pillar lamp of pleasing design wherein the arrangement is such as to afford a combined reflector and shield which 25 may be readily adjusted so as to protect the eyes of the driver from the rays of the lamp, and at the same time direct said rays in a manner to assist in illuminating the road in front and at the side of the car.

30 A further object is to provide a simple and convenient method of assembling the parts, and for rendering the shield and reflector movable with the lamp globe to facilitate the adjustment thereof.

35 A further object is to provide for mounting the globe in a manner to obviate the liability of breakage and facilitate its removal from the supporting arms of the bracket.

40 The above objects are attained by the structure illustrated in the accompanying drawings, in which:

Figure 1 is an elevation of a lamp embodying my invention, showing by dotted 45 lines the employment of the cap and lower supporting arm. Fig. 2 is a similar view partly in section. Fig. 3 is a horizontal section as on line 3—3 of Fig. 1, the bulb and reflector being omitted. Fig. 4 is an 50 elevation showing the lower supporting arm swung away from the bottom of the globe, and the globe withdrawn upon the cap preparatory to its removal. Fig. 5 is an enlarged fragmentary view in section showing 55 the upper end of the globe in contact with

the rubber washer carried at the perimeter of the circular plate or disk in the upper portion of the lamp, and in which the socket of the bulb is mounted. Fig. 6 is a horizontal section through the bulb socket as on line 6—6 of Fig. 5, showing a clamping ring embracing said socket to which the combined reflector and shield is attached.

Referring to the characters of reference, 1 designates a bracket adapted to be attached to a fixed support 2, as shown in Fig. 3, by means of machine screws 3 which pass through said support and enter tapped apertures in said bracket. This method of attaching the bracket removes all projecting parts from the face thereof. At the end of said bracket it is provided with extending feet 4 to afford the necessary bearing surface. The upper end of the bracket 1 is provided with a socket 5, as shown in Fig. 2. Fixedly secured in said socket and extending therefrom is an upper tubular arm 6 which curves outwardly. Mounted upon and carried by the upper end of said arm is a hollow head 7. In the lower portion of the head 7 is a tapped recess 8 into which screws the threaded stem 9 of the hood or cap 10 of the lamp. The cap 10 is dished and is adapted to receive the upper end of the glass globe 11.

The lower end of the bracket 1 is provided with a tapped aperture into which is screwed the threaded upper end 12 of the lower curved arm 13, thereby establishing a jointed connection between the lower arm and bracket which enables the free end of said arm to be swung in the arc of a horizontal circle as illustrated by dotted lines in Fig. 1 and by solid lines in Fig. 4. Mounted on the lower end of the arm 13 is a fitting 14 having a socket in the top thereof adapted to receive the reduced lower end of the lamp globe.

The socket 15 of the electric bulb 16 is mounted in the circular disk 17 so as to cause said bulb to depend centrally therefrom. Connected to the socket 15 are the service wires 18 which pass through the head 7, the tubular arm 6, and through the bracket 1, as shown in Fig. 2. The service or conductor wires 18 serve to effect a flexible connection between the cap and disk 17 and to hold said disk within said cap.

The disk 17 is adapted to close the upper end of the globe and is supported thereon in

such position as to cause the bulb to depend properly within the globe of the lamp, there being a washer of rubber or other compressible material 19 interposed between the 5 circumferential flange of said disk and the top of said globe. By employing a compressible washer in this manner a cushion is interposed between the disk 17 and the top of the lamp globe which obviates the liability of breakage and at the same time effects a tight joint between said parts which excludes dust from the interior of the globe. For a like reason there is interposed between the lower end of the globe and the 10 fitting 14 a compressible washer 20 which lies in the recess in said fitting, and upon which the lower end of the globe rests, as clearly shown in Fig. 2. To secure the lamp globe between the ends of the supporting 15 arms of the bracket, the cap 10, when the parts are properly in position, is turned so as to screw its threaded stem 9 out of the tapped recess in the head 7 thereby forcing it downwardly onto the disk 17 and in turn 20 causing the washer 19 on said disk to bear forcibly upon the upper end of the globe. This downward pressure exerted by the said cap also firmly seats the lower end of the globe in the fitting 14 upon the washer 20, 25 thereby securely mounting the globe between the ends of the curved supporting arms in a manner to obviate the liability of breakage, and at the same time eliminate all rattling of the connected parts.

30 35 Mounted upon the socket 15 is a split collar 21, through the ears 22 of which passes a clamping bolt 23. Hanging from said bolt is a combined reflector and shield 24 which is concavo-convex in form and provided 40 with a polished inner face. It will be noted that the collar 21 is vertically adjustable on the socket 15 whereby the reflector may be adjusted to properly focus the burner therein. The bolt 23 serves as a pivot on 45 which the reflector may be swung to cause it to project the rays of light at the desired angle.

The friction created by contact between the top of the globe and the rubber washer 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

to shield the eyes of the driver it will still project the rays of light forwardly and to the side. This method of adjusting the reflector and shield is very convenient as it does not require that the lamp be opened for this purpose.

When it is desired to remove the globe the stem of the cap is screwed upwardly into the recess in the head 7 such distance as to enable the bottom of the globe to be lifted from the fitting 14 when the arm 13 may be swung to one side upon its threaded connection with the bracket 1, as shown in Fig. 4, allowing the globe to be freely removed, the opening in the top of the globe being of sufficient size to allow the reflector to pass therethrough.

It has been previously explained that the curved arm 6 is rigidly secured in the bracket 1. Therefore when the parts are assembled as shown in Figs. 1 and 2 and the cap screwed downwardly over the upper end of the globe all of the parts are firmly held in place.

Having thus fully set forth my invention, what I claim as new and desire to secure by Letters Patent, is:—

1. A lamp comprising supporting members, a globe held at its ends between said members to rotate, a bulb socket member connected to said globe to turn therewith, and a reflector mounted on and rotatable with said socket member as the globe is turned.

2. A lamp comprising supporting arms, a globe adapted to be mounted between said arms and supported thereby, a member carried by one of the arms movably connected therewith to enable it to be moved into engagement with said globe, and one of said supporting arms being movably mounted to enable it to be swung from supporting relation with the globe of the lamp.

3. A lamp comprising a bracket, supporting arms mounted thereon, a lamp globe, a fitting on the lower arm to receive the bottom of said globe, a vertically moving cap on the upper arm to embrace the globe at the top, a disk within said cap, a compressible washer on said disk engaging the upper end of said globe, a bulb socket member mounted in said disk and depending into the lamp globe, a bulb in the socket of said member, and a reflector adjustably mounted on the socket member of the bulb.

In testimony whereof, I sign this specification in the presence of two witnesses.

WILLIAM T. JONES.
